UNITED STATES PATENT OFFICE

JOHN PUGEL, OF ELIZABETH, NEW JERSEY

RAILROAD TIE PROTECTOR

Application filed October 11, 1930. Serial No. 487,948.

This invention relates to protecting devices for wooden railroad ties, and has for its main object to provide a device which will prevent a cracking and subsequent rotting of the ends of such ties.

It is a well known fact that the ends of said wooden railroad ties are liable to crack during use and to rot and decay through such cracks and my invention mainly consists in providing a ring like structure around the tie adjacent to its end tightly drawn around the same and secured thereto which will prevent the cracking and separating of the material of the ends of said railroad ties, and at the same time such protecting device may also have extensions to be bent over and upon the ends of the tie so as to further protect the same from rotting.

Other objects of my invention are to provide a device of the character mentioned which will be simple and inexpensive in construction and efficient in use.

In the accompanying drawings forming a part of this specification:

Fig. 1 is an end elevation of a wooden railroad tie showing one embodiment of my invention applied thereto;

Fig. 2 is a perspective view of a portion of a railroad tie adjacent to its end showing another form of my device, while

Fig. 3 is an end elevation of the tie and protecting device shown in Fig. 2,

Fig. 4 is a perspective view of an end of the tie showing another modification of my protecting device applied thereto, and

Fig. 5 is a blank of still another modification of my device before being applied to the tie and broadly representing the device shown in Figs. 2 and 3 with extensions added at one side thereof to be bent over and fastened to the ends of the tie.

Referring now more closely by characters of reference and particularly to Fig. 1, the numeral 10 indicates a wooden railroad tie, adjacent to the one end of which a metal band 11 is wound around, tightly drawn over the tie. Apertures 12 are provided at appropriate places in the metal band, and nails, screws or other securing elements may be driven through the apertures 12 into the ma-

terial of the tie 10 to secure the band 11 in its tightly drawn position around the tie. The ends 11a and 11b of the band may overlap one another and may be secured together on the tie by similar securing means 13. It will be obvious that even this simple form of my invention will keep the material of the tie near its end tightly together and prevent the cracking or splitting of said material with its subsequent rotting and deteriorating.

An improved form of my device is shown in Figs. 2 and 3, wherein the protecting band 14 has prongs 15 struck out from the same at appropriate places so that a few prongs will be driven into each side of the tie when the band is tightly drawn around the same and by this simple means the ends of the tie will be kept tightly compressed and the cracking or splitting thereof prevented.

A modified form of the embodiment of Figs. 2 and 3 is shown in Fig. 5 in which extensions 16 are provided at the one side of the band 14 having inclined sides 17 so that when the band is tightly drawn and secured right at the end of the tie, said extensions may be bent over the end surface of the tie and through prongs 18 driven into the material to secure the same into its end surface and to cover and protect it by said extensions.

In Fig. 4, finally, I show a still further modification of my railroad tie protecting device in which the band around the tie and the protecting cover on its end surface are made up of four angular sections 19, 20, 21 and 22, each section covering one corner of said tie and to be secured thereto by nails or screws 23, the meeting edges of the sections overlapping one another, as at 24, and being secured to one another and to the material of the tie and its end surface by similar securing means 23.

It will be understood that changes and variations may be made in the parts and combinations of my device and I hereby reserve my rights to any and all such changes and modifications as are within the spirit of the invention and the scope of the annexed claims.

What I claim as new, is:

1. A protecting device for wooden railroad ties, comprising an element encircling said tie

adjacent to the end thereof, being tightly wound around the same and secured thereto so as to prevent the cracking or splitting of said end, said element being in the form of a metal band, and having prongs struck out from the material of said band adapted to engage the sides of said tie.

2. A protecting device for wooden railroad ties, comprising an element encircling said tie adjacent to the end thereof, being tightly wound around the same and secured thereto so as to prevent the cracking or splitting of said end, said element being in the form of a metal band, extensions applied along one edge of said band, said extensions being adapted to be bent over the end surface of the tie to cover and protect the same.

3. A protecting device for wooden railroad ties, comprising an element encircling said tie adjacent to the end thereof being tightly wound around the same and secured thereto so as to prevent the cracking or splitting of said end, said element being in the form of a metal band, prongs struck out from the material of said band adapted to engage the sides of said tie, extensions being provided along one edge of said band adapted to be bent over and cover and protect the end surface of the tie, said extensions also having prongs to engage the material of the tie.

Signed at New York, in the county of New York, and State of New York, this 2nd day of September, 1930.

JOHN PUGEL.
